(57) **CLAIM**

The ornamental design for a light source with reflective optic as shown and described.

DESCRIPTION

FIG. 1 is a perspective view the first embodiment of a light source with reflective optic, showing our new design;
FIG. 2 is a top view of the first embodiment;
FIG. 3 is a bottom view of the first embodiment;
FIG. 4 is a left side view of the first embodiment;
FIG. 5 is a right side view of the first embodiment;
FIG. 6 is a front side view of the first embodiment;
FIG. 7 is a rear side view of the first embodiment;
FIG. 8 is a perspective view of a second embodiment;
FIG. 9 is a top view of the second embodiment;
FIG. 10 is a bottom view of the second embodiment;
FIG. 11 is a left side view of the second embodiment;
FIG. 12 is a right side view of the second embodiment;
FIG. 13 is a front side view of the second embodiment;
FIG. 14 is a rear side view of the second embodiment;
FIG. 15 is a perspective view of a third embodiment;
FIG. 16 is a top view of the third embodiment;
FIG. 17 is a bottom view of the third embodiment;
FIG. 18 is a left side view of the third embodiment;
FIG. 19 is a right side view of the third embodiment;
FIG. 20 is a front side view of the third embodiment;
FIG. 21 is a rear side view of the third embodiment;
FIG. 22 is a perspective view of a fourth embodiment;
FIG. 23 is a top view of the fourth embodiment;
FIG. 24 is a bottom view of the fourth embodiment;
FIG. 25 is a left side view of the fourth embodiment;
FIG. 26 is a right side view of the fourth embodiment;
FIG. 27 is a front side view of the fourth embodiment; and,
FIG. 28 is a rear side view of the fourth embodiment.
The features illustrated with broken lines form no part of the claimed designs, and are included for the purpose of illustrating the entire light source with reflective optic. The bottom views are hidden in use and form no part of the
